(57) **CLAIM**

The ornamental design for a handheld drum auger, as shown and described.

DESCRIPTION

FIG. 1 is a perspective view of a handheld drum auger showing our new design;

FIG. 2 is a top plan view thereof;

FIG. 3 is a left side view thereof, the opposite side being a mirror image of the side shown;

FIG. 4 is a bottom view thereof;

FIG. 5 is a rear view thereof; and,

FIG. 6 is a front view thereof.

The broken line showing of details in FIGS. 1-5 is included for the purpose of showing environmental portions of the handheld drum auger and forms no part of the claimed design.

1 Claim, 3 Drawing Sheets
